US00D954005S

(12) **United States Design Patent** (10) Patent No.: **US D954,005 S**
(45) Date of Patent: ** *Jun. 7, 2022

(54) **HEATSINK**

(71) Applicant: **Furukawa Electric Co., Ltd.**, Tokyo (JP)

(72) Inventors: **Yoshikatsu Inagaki**, Tokyo (JP); **Shuta Hikichi**, Tokyo (JP)

(73) Assignee: **Furukawa Electric Co., Ltd.**, Tokyo (JP)

(*) Notice: This patent is subject to a terminal disclaimer.

(**) Term: **15 Years**

(21) Appl. No.: **29/727,572**

(22) Filed: **Mar. 11, 2020**

(30) **Foreign Application Priority Data**

Sep. 12, 2019 (JP) 2019-20398
(51) LOC (13) Cl. **13-03**

(52) U.S. Cl. USPC **D13/179**

(57) **CLAIM**

The ornamental design for a heatsink, as shown and described.

DESCRIPTION

FIG. 1 shows a top isometric view of a heatsink in accordance with the present design.

FIG. 2 shows a bottom isometric view of the heatsink in FIG. 1.

FIG. 3 shows a top view of the heatsink in FIG. 1.

FIG. 4 shows a bottom view of the heatsink in FIG. 1.

FIG. 5 shows a right side view of the heatsink in FIG. 1.

FIG. 6 shows a left side view of the heatsink in FIG. 1.

FIG. 7 shows a front view of the heatsink in FIG. 1; and,

FIG. 8 shows a rear view of the heatsink in FIG. 1.

The even broken lines illustrate environment that forms no part of the claimed design. The dot-dash broken lines represent boundary lines and form no part of the claimed design.

1 Claim, 6 Drawing Sheets
